UNITED STATES PATENT OFFICE.

JOHN N. NELSON, OF ROCHESTER, NEW YORK, ASSIGNOR TO E. KIRSTEIN SONS COMPANY, OF ROCHESTER, NEW YORK, A CORPORATION.

OPHTHALMIC MOUNTING.

1,263,593.

Specification of Letters Patent.

Patented Apr. 23, 1918.

Application filed November 30, 1917. Serial No. 204,600.

To all whom it may concern:

Be it known that I, JOHN N. NELSON, a subject of the King of Sweden, and resident of Rochester, in the county of Monroe and 5 State of New York, have invented certain new and useful Improvements in Ophthalmic Mountings, of which the following is a specification.

The present invention relates to ophthalmic mountings, and more particularly to the type in which the lenses are connected by a substantially rigid bridge or support, and a pair of nose guards are pivotally mounted on the support and held toward the nose under the action of springs, the nose guards having forwardly extending finger pieces by which the nose engaging portions of the guards are moved away from each other against the action of the springs. An object 10 of this invention is to provide an improved construction whereby the guards may be removed from the support for the lenses without removing the pivot pins on which the guards are mounted to turn, this removal 15 being effected without the provision of any separate parts on the mounting.

To this and other ends the invention consists of certain parts and combinations of parts all of which will be hereinafter described, the novel features being pointed out 20 in the appended claims.

In the drawings:—

Figure 1 is a plan view of a mounting constructed in accordance with the present 25 invention;

Fig. 2 is a transverse section through the mounting in the plane of one of the pivot pins;

Fig. 3 is a perspective of a portion of one 30 of the guard levers;

Fig. 4 is an enlarged sectional view of another embodiment of the invention; and

Fig. 5 is a perspective view of the pivot pin.

Referring more particularly to the drawings, A indicates the lenses which are connected by the support comprising, in this instance, the bridging portion 1 connected to the lens attaching devices 2 by connecting portions or tables 3. Mounted to swing 45 on the connecting portions 3 of the support are the guard levers 4 having the forwardly extending finger pieces 5 at their forward ends and the nose bearing portions 6 at their rear ends. Pivotal connection between each 50

of the guards and the support is, in this instance, formed by a pivot pin, which is anchored in one of the parts. In the illustrated embodiment the pivot pin is anchored in the support, and to this end the table or connecting portion 3 of the support is provided with a perforation through which a reduced portion 7 on the pivot pin passes, the lower end of the pivot pin being upset at 8^a on the under side of the support, while 60 the shoulder 9 between the reduced portion 7 and the bearing portion 8 engages the upper side of the support. The pivot pin is so secured to the support that, while under ordinary conditions it will be held against 65 turning, yet, if a screw driver be connected to the upper end thereof through the recess 10, the pivot pin may be turned. In the embodiment shown in Fig. 4, a spring washer 11 is interposed between the upset 70 end 8^a of the pivot pin and the connecting portion 3 of the support to more readily facilitate the turning of the pivot pin in the support.

The purpose of turning this pivot pin is 75 to permit the lateral projection 12 on the free end of the pivot pin to be brought into alignment with the slot or recess 13^a formed in the bearing portion of the guard lever, so that, when the projection 12 and the recess 80 are aligned, the guard lever may be fitted to or removed from the bearing portion 8 of the pivot pin. In the illustrated embodiment 85 the guard lever has a tubular portion 13 projecting from the upper side thereof and formed with a rib or shoulder 14 at its upper end. The coil spring 15 surrounds the tubular portion 13 and has one end 16 secured to the guard lever while the other end 17 bears against the support for the lenses. 90 With this arrangement the spring is carried by the guard lever and may be removed from or fitted to the mounting with such guard lever. The tubular portion also provides an extended bearing for the guard 95 lever and prevents wabbling of the latter on the pivot pin.

It will be apparent that to remove the guard lever, or fit the same to the mounting, the pivot pin is turned relatively to the support for the lenses, until the projection 12 is aligned with the slot 13^a, after which the movement of the guard lever axially on or off the pivot pin will be permitted. After 100 the guard lever is placed on the pivot pin, 110

the latter is then turned to bring the projection 12 above the upper end of the tubular portion 13 to lock the guard lever in place.

5 With this arrangement the formation of screw threads in the support for the lenses and also on the pivot pin is obviated, and, at the same time, the pivot pin is maintained permanently in connection with the support 10 for the lenses or part in which it turns, so that the loss of the pivot pin, which frequently occurs with the removal of the guard, is eliminated.

15 What I claim as my invention and desire to secure by Letters Patent is:—

1. An ophthalmic mounting comprising a support for the lenses, a nose guard and a pivot pin anchored and rotatable in one of said parts, and having a bearing in the 20 other part to permit a free turning movement between such other part and the pivot pin, the pivot pin and such other part having provision for permitting the said other part being disconnected from the pivot pin 25 when the latter is turned in but not removed from the part in which said pin is anchored.

2. An ophthalmic mounting comprising a

support for the lenses, a nose guard, and a pivot pin anchored and rotatable in one of said parts and having a bearing in the other part to permit a free turning between such other part and the pivot pin, the said other part being provided with a lateral slot in its bearing part and the pivot pin having a projection adapted to pass through said slot on a relative axial movement between the pivot pin and the said other part, said projection being arranged to be engaged with or disengaged from said other part on the rotation of the pivot pin in the part in which the pin is anchored.

3. An ophthalmic mounting comprising a support for the lenses, a pivot pin anchored in and rotatable in the support, said pivot pin having a bearing portion and a lateral projection at the end of the bearing portion, a nose guard mounted to turn on the pivot pin and having a lateral slot in its bearing through which the lateral projection of the pivot pin is adapted to pass in order to permit the nose guard to be fitted to or to be removed from the mounting.
